UNITED STATES PATENT OFFICE.

LEONHARD BAUROTH, OF TOLEDO, OHIO, ASSIGNOR TO THE METALLIC BARREL COMPANY, OF CHICAGO, ILLINOIS, A CORPORATION OF MAINE.

SHEET-METAL BARREL.

1,120,889.

Specification of Letters Patent.

Patented Dec. 15, 1914.

Application filed November 21, 1908. Serial No. 463,819.

To all whom it may concern:

Be it known that I, LEONHARD BAUROTH, a citizen of the United States, and a resident of Toledo, in the county of Lucas and State of Ohio, have invented a certain new and useful Sheet-Metal Barrel; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to metallic receptacles, and particularly to sheet-metal barrels of the class having spaced crimps or ribs formed longitudinally thereof to strengthen them against compression. In order to render barrels of this nature sufficiently strong to resist the external compressing stresses to which they are subjected in ordinary use it has been necessary to employ other means than longitudinal crimps, for instance, an internal spider, to strengthen the barrels against compression.

The object of my invention is to produce a metallic barrel or receptacle of the character stated dispensing with such internal spider or the like, and provided with simple, efficient and reliable means for obtaining the proper strengthening effect against external compressing forces, with the result that my barrel or receptacle possesses the necessary strength and rigidity without obstruction to the interior of the barrel or without lessening the capacity thereof.

Further objects of the invention, as well as the construction and arrangement of the parts thereof, are fully described in the following specification, and a preferred embodiment thereof illustrated in the accompanying drawings, in which,—

Figure 1 is a side elevation of a barrel embodying my invention, with portions of the same broken away. Fig. 2 is an end view thereof with a portion in section on the line $x-x$ in Fig. 1. Fig. 3 is an enlarged elevation of a portion of the barrel, with the part A B thereof in vertical section, as on the line $x'-x'$ in Fig. 2, and the part A C thereof in vertical section, as on the line $y-y$ in Fig. 2; and Fig. 4 is an enlarged portion of one end of the barrel with the head removed.

Referring to the drawings, 5 designates the body of the barrel, and 6, 6 the opposing heads thereof. The body 5 is preferably formed from a cylindrical sheet-metal blank, which is provided with the inwardly-projecting longitudinally-extending crimps or furrows 7, at suitably spaced distances therearound, which serve both to strengthen the body against external compressing stresses and to impart the desired bilge formation thereto, which latter is accomplished by gradually deepening the crimps from the center toward the ends thereof to proportionately increase the amount of metal taken up thereby. I wish it understood, however, that I do not wish to restrict my invention to use in connection with any particular shape or formation of receptacle, whether of bilge form or otherwise, or to any particular manner of forming the same.

In the base of each of the crimps or furrows 7 is disposed a reinforcing rod or heavy wire 8, which is firmly held therein by drawing the outer opposing edges of the crimp together so that they abut, or substantially abut, as shown at 9, Figs. 2 and 4. The closing of the mouths of the crimps also gives one side of the package the appearance of a substantially plain or uninterrupted surface. In order to prevent a longitudinal movement of the rods within the crimps, their ends are terminated short of the ends of the crimps, as shown in Fig. 3, and the ends of the crimps bent laterally or radially and flattened against the inner end portions of the body, as shown at 10, thus closing the ends of the crimps over the rod ends and forming internal shoulders 11 upon which the heads 6, 6 may seat. By securing the rods 8 within the crimps in this manner it is evident that the barrel body is made very rigid in its construction and is capable of resisting very great external forces; and also that the bending of the crimp ends closely over the rod ends and radially flattening them against the receptacle body absolutely secures the rods against longitudinal movements within the crimps, reinforces the body chime and forms firm, rigid seats for the receptacle heads.

In the present instance the body 5 is encircled by a plurality of hoops 12, which are riveted or secured thereto in any other suitable manner, and prevent an expansion of 5 the body or an opening of the crimps from their closely compressed state, as shown.

The heads 6 are shown as being stamped from sheet-metal and have their major portions depressed to adapt them to fit snugly 10 within the end portions or chimes of the barrel and seat on the shoulders 11 formed at the end portions of the crimps. The chime at each end of the body 5 has its edge preferably rolled outwardly to form a hooked 15 edge with which the marginal edge of the respective head 6 may engage, said edge of the head being rolled over the chime and interlocking with the edge thereof, as shown at 13, Fig. 1, and the whole then closely compressed to form a firm joint. To prevent 20 an opening of the joint thus formed the end of the barrel is encircled by a hoop or band 14, which is secured in position by rivets 15, or the like, passing through it, 25 the chime and outwardly projecting portion of the head. It will be understood, of course, that the heads of a barrel are not intended to be taken off after once being placed thereon, as the barrel is filled and the 30 contents withdrawn therefrom through the bung-hole 16.

I desire it to be understood that my in-

vention is not limited to any specific form or arrangement of parts, except in so far as such limitations are specified in the claim. 35

Having thus described my invention, what I claim as new and desire to secure by Letters Patent, is,—

A bilged metallic receptacle having a plurality of inwardly projecting crimps formed 40 longitudinally thereof, a reinforcing rod disposed within each crimp and bowed to conform to the bilge of the receptacle with the mouths of the crimps drawn closely together around the rods to retain them therein and 45 to provide the receptacle with a substantially uninterrupted circumferential surface, said rods having their ends standing inward a greater distance from the receptacle wall than the central portions thereof and termin- 50ating short of the respective ends of the receptacle, and the crimp ends being bent closely over the rod ends and flat against the receptacle body whereby to secure the rods in place and to coöperate with the instand- 55ing ends thereof to form firm seats for the receptacle heads, substantially as described.

In testimony whereof I have hereunto signed my name to this specification in the presence of two subscribing witnesses.

LEONHARD BAUROTH.
